UNITED STATES PATENT OFFICE.

ARCH D. COWAN, OF FULTON, ILLINOIS, ASSIGNOR TO PATENT NOVELTY COMPANY, OF FULTON, ILLINOIS, A CORPORATION OF ILLINOIS.

DESIGN FOR A MAIL BOX.

Application filed August 11, 1927. Serial No. 23,060. Term of patent 3½ years.

To all whom it may concern:

Be it known that I, ARCH D. COWAN, a citizen of the United States, and a resident of Fulton, in the county of Whiteside and State of Illinois, have invented a new, original, and ornamental Design for a Mail Box, of which the following is a specification, reference being had to the accompanying drawing, forming a part thereof.

Fig. 1 is a front elevation of the mail box, embodying my new and ornamental design.

Fig. 2 is a side elevation of the mail box, embodying my new and ornamental design.

I claim:

The ornamental design for a mail box, as shown.

ARCH D. COWAN.
